UNITED STATES PATENT OFFICE.

CASPER E. YOUNGCHILD AND BERTRAM T. MCBAIN, OF PORT EDWARDS, WISCONSIN.

PULP-BEATER ROLL.

Application filed March 3, 1923. Serial No. 622,506.

To all whom it may concern:

Be it known that we, CASPER E. YOUNGCHILD and BERTRAM T. MCBAIN, citizens of the United States, and residents of Port Edwards, in the county of Wood and State of Wisconsin, have invented certain new and useful Improvements in a Pulp-Beater Roll; and we do hereby declare that the following is a full, clear, and exact description of the same, reference being had to the accompanying drawings, and to the numerals of reference marked thereon, which form a part of this specification.

This invention relates to paper making machines and more particularly to an improved type of pulp beater roll provided with built-up fillers to greatly increase the beater surface, said roll adapted for use in a beating engine or Hollander type of beater to prepare stock or pulp so that the pulp fibres will more closely mat when being formed into paper in a paper making machine.

It is an object of this invention to provide a beater roll with additional filler bars secured between alternate sets of fly bars, said filler bars and fly bars being built-up on their tread surfaces by welding material thereon.

It is also an object of the invention to provide a beater roll with additional built-up fillings adapted to increase the beating surface of the roll about double without reducing the number of circulations of the pulp or stock in the beater tank, nor the thickness or consistency of said pulp or stock.

Another object of the invention is to reclaim old beater rolls by securing auxiliary filler bars between alternate pairs of the roll fly bars, and then using the old fly bars as a base upon which material is welded to provide tread flanges which are ground to afford a tread surface for the roll.

It is a further object of the invention to provide a beater roll wherein the fly bars have secured thereto filler bars which together with said fly bars are built-up by welding material thereto which when worn down by usage can be rewelded or built-up, making the life of the beater roll substantially perpetual.

It is furthermore an object of this invention to provide a method for increasing the beating surface of an old beater roll by securing additional filler bars between alternate pairs of the beater roll fly bars and

then building up the fly bars and the additional filler bars by welding material thereto, after which the built-up beater roll is ground to afford a true circular tread surface.

It is an important object of the invention to provide an improved beater roll wherein the life of the old fly bars is increased and the beating capacity substantially doubled by securing additional fillings in place between the old fly bars and then building up the fly bars and the fillings by welding material thereto, after which the built-up beater roll is ground to afford a true circular beater surface in which every bar does its share of the work when coacting with the machine bed plate which is planed to the exact arc of the built-up roll.

Other and further important objects of this invention will be apparent from the disclosures in the drawings and specification.

The invention (in a preferred form) is illustrated in the drawings and hereinafter more fully described.

On the drawings:

Figure 1 is an end elevation of a beater roll embodying the principles of this invention.

Figure 2 is an enlarged fragmentary developed portion of the peripheral face of the beater roll.

Figure 3 is a fragmentary section taken on line 3—3 of Figure 2.

Figure 4 is a fragmentary perspective view of a modified form of beater roll.

Figure 5 is a fragmentary plan view of one of the beater fillings.

Figure 6 is an end view thereof.

Figure 7 is a transverse section thereof taken on line 7—7 of Figure 5.

As shown on the drawings:

The reference numeral 1 indicates a beater roll drum provided with a supporting shaft 2. The periphery of the drum 1 is made up of a plurality of spaced wooden staves or boards 3 disposed longitudinally of the drum. Rigidly secured between adjacent staves 3 are radially projecting steel fly bars 4 which extend the length of the drum. Welded or otherwise securely fastened at right angles between alternate pairs of the fly bars 4 are staggered spacer bars 5. Rigidly secured by welding or by other suitable means between each pair of the remaining alternate pairs of the fly bars 4 are a plurality of filler bars 6 arranged in a zig-

zag fashion at right angles to one another between the fly bars with the ends of the filler bars cut to contact one another and abut against the fly bars at an angle of 45°, 5 as illustrated in Figure 2.

After the spacer bars 5 and the filler bars 6 have been secured in place by electrically welding them between the original or old 10 filler bars or fly bars 4, said fly bars 4 together with the spacer bars 5 and the auxiliary filler bars 6 are used as a base and built-up by welding material thereon to afford tread flanges or ribs 7 for the beater roll. When the beater roll has been built-up 15 sufficiently, the beater roll is mounted in place above a beater roll grinder and the face of the beater roll is ground to afford a true circular tread surface thereby insuring that each of the bars on the 20 periphery of the drum 1 will do its respective share of the work.

The beater roll when properly ground to form is adapted to coact with a bed plate 8 forming a part of the pulp treating 25 machine or beater engine in which the beater roll is used.

In paper making plants, the pulp or stock is prepared as it comes from the pulp mills, by running the pulp into a beater tub or 30 tank in which the pulp is circulated or pulled through under the beater roll and between it and the bed plate so that the fibre will more closely mat or close on the paper making machine after leaving the 35 beater engine.

By equipping an old beater roll with the auxiliary filler bars 6 and the spacer bars 5, the beater surface of the roll is practically doubled without requiring any increase in the driving power and without 40 reducing the thickness or consistency of the pulp. The increase of the beater surface does not act to reduce the circulation of the pulp in the beater engine.

45 While the beater roll is improved by welding the spacer bars and the additional filler bars in place between the old fly bars, it will of course be understood that said spacer bars 5 and the filler bars 6 may be bolted or riveted in place or, if desired, secured by any other method. By welding on the tread material to the various old and new bars of the beater roll and then grinding the beater roll down to proper form, it 50 will be seen that the beater roll may be readily rewelded or built-up when it becomes worn, thereby making the life of the improved beater roll practically perpetual.

60 Figures 4 to 7 inclusive illustrate a modified form of improved beater roll wherein an old beater drum 9 having radially projecting steel fly bars 10 is used as a base for the new beater roll. The fly bars are rigidly secured between the staves 11 of the drum.

In this form of the beater roll, each alternate pair of fly bars 10 has seated thereon and rigidly secured thereto a cast beater filling or tread bar.

Each tread bar comprises a plate 12 provided with longitudinal notches or recesses 13 and with a plurality of longitudinal staggered slots 14. The plate 12 has integrally formed on the under side thereof longitudinal ribs or flanges 15 and 16 each having 75 lugs or studs 17 integrally formed on the outer side thereof.

Openings 18 are provided in the beater roll fly bars 10 in a position to register with the lugs 17 of the tread bars when the 80 tread bars are mounted in place as illustrated in Figure 4. Molten metal is poured into the tread bar recesses 13 and forms the fillings 19 and 20. The molten metal also flows into the fly bar openings 18 and 85 affords retaining means for holding the tread bars secured in position. After the tread bars are secured in place as described or by means of screws or rivets or other suitable means, a material is welded to each 90 tread bar to fill the recesses 13 and project therefrom to provide treads or ribs 21. The slots 14 of each tread bar are also filled by welding material to the tread bar with said material projecting to provide a plurality 95 of tread flanges or ribs 22. After the tread bars are all built-up with the tread flanges or ribs 21 and 22, the improved beater roll is mounted in place above a grinding plate and operated to cause the 100 beater roll to be ground to afford a true circular tread surface so that all of the built-up tread flanges 21 and 22 will do their respective share of the work when the beater roll is in use in a beater engine for 105 the purpose of preparing pulp for paper making machines.

It will be noted that by adding filler members to old beater rolls and then building up the beater roll fly bars as well as the filler members, that a beater roll of a greatly increased beating surface is provided without in any way acting to reduce the number of times the pulp is circulated in the beater tank or without reducing the thickness or consistency of the stock or pulp. With a built-up beater roll of the type described, no increase in the driving power is required to operate the beater roll.

Attention is directed to the fact that by 110 welding the spacer bars 5 and the filler bars 6 between the fly bars 4 as described, that a beater roll of great strength and substantially unitary or solid construction is produced. The steel bars or fillers 5 and 115 6 also serve to rigidly hold the wooden staves 3 secured in position. By welding the fillers 5 and 6 between the fly bars 4 reinforces said fly bars to such an extent that it is practically impossible to injure should 120 125 130

foreign matter such as pieces of iron or wrenches find their way into the beater. The additional filler bars, when welded in place, increase the beating surface over one 5 hundred per cent, and also tend to increase the life of the roll one hundred per cent at the same time. By welding the various bars together, as described, it is impossible for them to work out of place, even though 10 the retaining rings usually secured on the ends of the beater roll should come off or be omitted.

We are aware that numerous details of construction may be varied through a wide 15 range without departing from the principles of this invention, and we therefore do not purpose limiting the patent granted otherwise than necessitated by the prior art.

We claim as our invention:

20 1. A beater roll comprising a drum, fly bars rigidly secured radially on the periphery thereof, filler bars rigidly secured between alternate pairs of said fly bars, and material built-up on the tread surfaces of 25 said fly bars and of said filler bars to afford a tread for the beater roll.

2. A beater roll comprising a drum, metal fly bars rigidly secured thereto and projecting radially therefrom, filler bars rigidly secured in place between alternate pairs 30 of said fly bars, and tread flanges on said fly bars and on said filler bars provided by welding material thereto.

3. The combination with a beater roll 35 and the fly bars thereof, of filler bars welded in place between alternate pairs of said fly bars, and material welded to said fly bars and to said filler bars to afford tread flanges which may be built-up when 40 worn.

4. The combination with an old beater roll and the fly bars thereof, of filler members rigidly secured to said fly bars, and tread flanges formed on said filler members 45 by welding material thereto.

5. A beater engine beater roll comprising a drum, a shaft for supporting the same,

radially directed metal fly bars rigidly secured longitudinally of said drum, staggered spacer bars rigidly secured between alternate pairs of said fly bars, filler bars rigidly secured between the remaining alternate pairs of said fly bars, and tread flanges formed on said fly bars, said spacer bars and said filler bars by welding material 55 thereon.

6. The method of increasing the beating surface of a beater roll, consisting of rigidly securing additional filler members between the fly bars of a beater roll and then welding material to said fly bars and to said 60 filler members to form tread flanges.

7. The method of increasing the beating surface of a beater roll, said method consisting of welding filler bars and spacer 65 bars respectively between alternate pairs of the beater roll fly bars, and then building up the fly bars, the filler bars and the spacer bars by welding material to the tread surfaces thereof, after which the built-up beater 70 roll is finished by grinding the built-up portions to afford a true circular beater surface.

8. A beater roll comprising a drum, fly bars rigidly secured thereto and projecting radially therefrom, filler bars rigidly secured in place between alternate pairs of said fly bars with the tread surfaces of said filler bars flush with the tread surfaces of the fly bars, and tread flanges secured to the tread 75 faces of said fly bars and said filler bars.

9. The combination with a beater roll and the fly bars thereof, of filler members rigidly secured between said fly bars, and tread members rigidly secured on the tread faces 80 of said fly bars and of said filler members.

In testimony whereof, we have hereunto subscribed our names in the presence of two 85 subscribing witnesses.
